UNITED STATES PATENT OFFICE.

PHILIP A. MICHELL, OF NEW YORK, N. Y.

BAG-LOCK.

1,331,778.

Specification of Letters Patent. Patented Feb. 24, 1920.

Application filed October 22, 1918. Serial No. 259,216.

To all whom it may concern:

Be it known that I, PHILIP A. MICHELL, a citizen of the United States of America, residing at New York city, in the county of 5 New York and State of New York, have invented new and useful Improvements in Bag-Locks, of which the following is a specification.

The invention aims to provide as its principal object a device of the character embodying a casing with which there is associated a flexible engaging member. One end of the flexible member being secured to the casing while the other end thereof is 15 slidable through the casing and engageable by a locking member carried within the casings. Unique means is provided for disengaging the locking member from the flexible member when releasing the latter, and this 20 means is engageable by a key, so that suitable combinations can be formed whereby each lock can be so made as to be operated only by a particular key.

The further object of the invention is 25 the provision of a device of this character which is simple in construction, durable and effective in operation and inexpensive to manufacture.

Other and further objects appear in the 30 following description wherein the invention is set forth in detail.

As shown and described, a specific embodiment is adhered to, but to this embodiment the invention is restricted. The right is reserved to make such alterations and changes 35 as reduction of practice may suggest, in so far as such changes or alterations are compatible in spirit with the annexed claims.

In the accompanying drawings:

40 Figure 1 is a view in side elevation of the improved lock with the covering member for the casing removed, the locking member within the casing being shown in locked position.

45 Fig. 2 is a view similar to Fig. 1, but shows the locking member in unlocked position.

Fig. 3 is a section on the line 3—3 of Fig. 1.

50 Fig. 4 is a perspective view of the key barrel.

Fig. 5 is a perspective view of a locking member carried within the casing.

Fig. 6 is a perspective view of the element

by which the locking member is moved to 55 lock or unlocking position.

Fig. 7 is a perspective view of the combination plate whereby the lock may be made operable by a specified shape of key only.

Fig. 8 is a plan view of the key used with 60 the particular combination shown.

As shown, the invention comprises a flat hollow casing 1, on certain of whose side walls there are formed projections 2 in which there are formed holes 3 for the reception of suitable rivets by means of which a cover for securing the casing to house within the operating members of the lock. This cover is not shown in Figs. 1 and 2, but the lower portion thereof in which there is 65 formed an aperture forming a bearing for the key barrel appears in Fig. 3. Pivotaly carried upon a pin 5 which is fixed in the front wall of the casing 1 and also in the cover 4 there is a locking member 6 and this 70 locking member is formed in the peculiar shape shown and so mounted and so shaped that it may have one edge lie adjacent to one of the side walls of the casing. This side wall designated 7 is roughened on its inner 75 face, and that edge of the locking member adjacent this inner face is formed with a shallow groove 8 of curved formation in cross section.

The casing 1 of the interior is formed with 80 a lug 9 and this lug has fixed in it one end of a flat bodied spring 10, the free end of the latter bearing against one end of the locking member 6 and tending to keep its 85 grooved edge 8 forced over toward the 90 roughened inner face of the side wall 7 of the casing 1. A flexible member 11 has one end passed through an appropriate hole formed in the top side wall of the casing 1 and through a registered hole in the lug 9, 95 this end of the flexible member interior to the casing being knotted as shown at 12 so that the flexible member may not be withdrawn from the casing. At the opposite end of the interior end wall of the casing a second hole 13 is formed through which the other end of the flexible member 11 is admitted to the casing. This other end is designed to pass down through the casing and out through the bottom wall 100 through a hole 14, the portion lying within the casing being engaged by the groove edge 8 of the locking member 6, and forced 105

over against the roughened inner face of the wall 7. The pivotal point of the locking member 6, it will be observed, is nearer the top of the casing than is that part of the locking member which engages the flexible member 11. Therefore, any pull tending to draw the flexible member out of the casing when it is engaged by the locking member only tends to tighten the engagement of the latter with the flexible member, and thus precludes the withdrawal of the latter. The eye 15 by which the locking member 6 is pivotally mounted on the pin or stud 5 is of oval-shape as shown, so that the locking member may be assured of firm contact with the flexible member irrespective of any irregularities of diameter of the latter.

The locking member 6 is formed with a depending tail portion 16, which is slotted transversely to receive the end of a pawl 17. This pawl and locking member being pivotally connected together by means of a pin 18, as shown. The bottom edge of the pawl is formed with a plurality of teeth 19, which are designed for engagement by the teeth 20 carried upon a key barrel 21, the latter being pivotally mounted in the front wall of the casing 1, and the cover member 4 of the latter. This key barrel is formed with a radial slot 22 extending throughout its length and this slot is designed to receive a key 23, by which the key barrel is turned and its operation effective.

Fixed upon the bottom wall of the casing 35 there is a bar 24 whose upper edge is formed with the teeth 25 designed for engagement with the terminal tooth 26 formed on the pawl 17. Adjacent one end of the bar 24 and adjacent also to the barrel 21 there is an 40 angular ward plate 27, which is secured to the bottom wall of the casing, and so positioned that its upstanding portion which is slotted in the peculiar fashion shown at 28 may describe the shape of key necessary to 45 operate the barrel.

A flat spring 29 is fixed in the locking member 6, and its free edge bears on top of the pawl 17 and tends to keep the latter forced toward and in engagement with the 50 teeth 25 on the bar 24.

In the operation of the improved lock, the locking member 6 when in locked position, stands as shown in Fig. 1, and the end 26 of the pawl 17 engages between the two teeth 55 25 nearest the left. The barrel stands as shown with a vertical slot, and its teeth 20 just to the right of the last of the teeth 19 on the pawl. The elongated or oval shaped slot 15 in the locking member enables the 60 spring 10 to retain the locking member in a position where the flexible member 11 will be forced firmly against the roughened face of the side wall 7, and the flexible member is thus prevented from being withdrawn 65 from the casing. To release the flexible

member, the key 23 is inserted in the barrel after which the latter is moved angularly by turning the key, the slotted portion 28 of the ward plate 27 corresponding to the shape of the operating end of the key permitting the 70 key to pass and the barrel to be turned thereby. The operating end of the key, designated by 30, after the barrel has been turned through approximately 180 degrees encounters the teeth of the pawl 17 slightly 75 raising the latter and tending to force it and the connecting end of the locking member 6 toward the right. So soon as this end 30 of the key has moved far enough to disengage itself with the teeth of the pawl 17 the teeth 80 20 of the barrel engage with the teeth 19, and the pawl is thereby continued on its movement to the right, this operation swinging the locking member 6 on its pivot stud 5 so that when the terminal tooth 26 rests 85 between the two teeth 25 nearest the right the locking member will be swung away from the flexible member and that end of the flexible member which the locking member previously engaged may be withdrawn 90 through the casing.

It is obvious that the flexible member may be drawn taut around the necks or bags of same articles to lock them in closed position, and the peculiar construction of the 95 device makes it serviceable for a hand cuff or for any other purpose where a flexible locking member may be of service.

From the foregoing description and the accompanying drawings, it is believed that 100 a clear enough understanding of the invention is to be had to render further description unnecessary.

The invention having been described what 105 is claimed as new and useful is:

1. A lock of the character described comprising a casing, a flexible member having one end secured in the casing and extended to form a loop, the remaining end having a sliding engagement with the casing, a pivotally mounted locking member carried within the casing and having an edge engageable with the running end of the flexible member to force the latter against one wall of the casing, a spring tending to force 115 the locking member into such engagement with the flexible member, a key barrel pivotally mounted in the casing, a pawl pivotally connected with the locking member, a bar carried in the casing and having teeth engageable by the pawl, the pawl being formed on one edge with teeth, the barrel also being formed with teeth, and a key by which the barrel is moved angularly, the key first engaging the teeth of the pawl and the 120 teeth of the barrel thereafter engaging the pawl, whereby the locking member is swung to unlocked position against the pressure of the spring.

2. A lock of the character described com- 130

prising a casing, a flexible member having one end secured to the casing, and the other end in running engagement with the casing, a cam shaped locking member pivotally mounted in the casing and having one edge engageable with the running end of the said flexible member to force the same against

one side wall of the casing, a key barrel rotatably mounted in the casing, and operative connections between the key barrel and the 10 cam shaped locking member for the useful purpose specified.

In testimony whereof I affix my signature.

PHILIP A. MICHELL.
